(No Model.)

W. HINCHLIFFE.

MACHINE FOR ROLLING COTTON BATTING.

No. 276,402.

Patented Apr. 24, 1883.

Fig. 3.

UNITED STATES PATENT OFFICE.

WILLIAM HINCHLIFFE, OF NASHVILLE, TENNESSEE.

MACHINE FOR ROLLING COTTON-BATTING.

SPECIFICATION forming part of Letters Patent No. 276,402, dated April 24, 1883.

Application filed November 21, 1882. (No model.)

To all whom it may concern:

Be it known that I, WILLIAM HINCHLIFFE, a citizen of the United States, residing at Nashville, in the county of Davidson and State of Tennessee, have invented a new and useful Machine for Rolling Cotton-Batting, of which the following is a specification, reference being had to the accompanying drawings.

This invention relates to machines for rolling cotton-batting; and it consists in certain improvements in the construction of the same, which will be hereinafter fully described, and particularly pointed out in the claims.

In the drawings hereto annexed, Figure 1 is a perspective view of my invention complete and ready for operation. Fig. 2 is a longitudinal vertical sectional view, and Fig. 3 is a transverse vertical sectional view on the line *x x* in Fig. 2.

20 The same letters refer to the same parts in all the figures.

A in the drawings represents a trough or box, of which B is the bottom, and C D the sides. The side C is secured permanently to the bottom, while the side D is provided with laterally-projecting slotted lugs or plates to receive set-screws E E, which enter the bottom, and by which the said side D is made laterally adjustable. By thus adjusting the side D the box or trough may be adjusted so as to accommodate sheets of batting of various widths. The front end of the bottom of the box or trough has a hinged leaf, F, swinging vertically between the sides of the box. Said hinged leaf is forced automatically in an upward direction by means of a weighted cord or rope, G, attached to its outer end, and passing over a pulley, H, journaled to a post or upright, I, secured to the side of the box, as shown in the figures of the drawings; or said pulley may be journaled to a bracket depending from the ceiling, which, however, is not shown in the drawings. The sides C and D are provided near their front ends with openings J, forming bearings for a plain or fluted roller, K, having at one end a crank wheel or handle, L, by which it may be readily manipulated. The roller K is journaled loosely in its bearings, so that it may be readily withdrawn when desired. The upright I is provided with a laterally-projecting arm or bracket, M, extending over the trough or box. Journaled upon this arm or bracket is a flanged roller, N, which holds a roll of perforated paper adapted for wrapping the rolls of batting.

The flanges O of roller N are loose in order to permit a roll of paper to be slipped upon the roller without winding.

The operation of my invention will be readily understood from the foregoing description, taken in connection with the drawings hereto annexed. By adjusting the side D of the box it may be adapted to roll batting of any desired width without previously folding it. The end of the sheet is placed upon the roller K, which is then revolved, thus forming the roll. The hinged leaf F, by pressing upon the under side of the roll while being formed, gives the necessary tension, which may be easily regulated by adding to or taking from the weight O² at the end of the rope G, as may be required.

When the roll has been finished it is wrapped in paper from the roll upon the roller N, the wrapper is gummed or otherwise secured, and the roller K is then withdrawn, thus enabling the roll of batting to be removed from the machine.

If desired, the rope, pulley, and weight G, H, and O² may be dispensed with, and any other equivalent mechanism substituted for forcing the hinged leaf F in an upward direction. Thus, for instance, I have shown in dotted lines in Fig. 2 an arrangement of levers and a weight which may be successfully used for this purpose.

I claim as my invention and desire to secure by Letters Patent of the United States—

1. The combination, with the trough or box having an adjustable side and a hinged leaf, as described, of the detachable winding-roller journaled in the front ends of the sides of the box, as set forth.

2. The combination of the trough or box having an adjustable side and a hinged leaf, as described, means for forcing said leaf in an upward direction with any desired degree of pressure, the detachable winding-roller, and a post or upright having a laterally-projecting arm extending over the trough or box, and adapted to carry a roll of wrapping-paper, as and for the purpose shown and specified.

In testimony that I claim the foregoing as my own I have hereto affixed my signature in presence of two witnesses.

WILLIAM HINCHLIFFE.

Witnesses:

D. R. BOWLING,
CAMPBELL LEWIS.
